(57) **CLAIM**

The ornamental design for a soilless cultivation device, as shown and described.

DESCRIPTION

FIG. 1 is a perspective view of a soilless cultivation device; FIG. 2 is another perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is an enlarged partial view showing a part labeled 9 in FIG. 1, showing my new design.

The evenly dashed broken lines depict portions of the soilless cultivation device that form no part of the claimed design. The short dash-long dash broken lines encircling a portion of the soilless cultivation device in FIG. 1 and the enlarged view in FIG. 9 indicate areas of the figures shown enlarged which form no part of the claimed design.
